UNITED STATES PATENT OFFICE.

LEWIS E. SUMMERS, OF DETROIT, MICHIGAN, ASSIGNOR TO CHICAGO PNEUMATIC TOOL COMPANY, OF CHICAGO, ILLINOIS, A CORPORATION OF NEW JERSEY.

PNEUMATIC HAMMER.

1,115,985.

Specification of Letters Patent.

Patented Nov. 3, 1914.

Application filed November 11, 1913. Serial No. 800,291.

To all whom it may concern:

Be it known that I, LEWIS E. SUMMERS, a citizen of the United States, residing at Detroit, in the county of Wayne and State 5 of Michigan, have invented certain new and useful Improvements in Pneumatic Hammers, of which the following is a specification.

My invention relates to a pneumatic hammer, more particularly a riveting hammer and the object thereof is to provide a working tool such as a rivet-set which shall be detachably connected with the front end of the hammer barrel or cylinder and be retained in working position against any possibility of detachment or expulsion while in use. I successfully accomplish these results by my form of hammer and rivet-set and at the same time I provide for a shortening of the set itself and of the barrel or cylinder with the result that the same work may be accomplished by means of a shorter and lighter hammer, representing an advantage in addition to the safety feature 25 and positive holding means for the rivet-set.

Other novel and advantageous features of construction in my new form of hammer will be understood from the description 30 hereinafter given.

In the drawings, Figure 1 is a longitudinal sectional elevation of a pneumatic hammer embodying my invention; Fig. 2 an end view of the front end of the hammer 35 or barrel; Fig. 3 an enlarged sectional elevation of the front end of the hammer; Fig. 4 an elevation of the front end of the hammer; Fig. 5 a section on the line 4-4 of Fig. 3 and Figs. 6, 7, 8 and 9 perspectives 40 illustrating separately the parts shown assembled in Fig. 3, Fig. 6 being a perspective of the front end of the cylinder, Fig. 7 a perspective of the rivet-set, Fig. 8 a perspective of the spring and Fig. 9 a perspective 45 of the sleeve.

It will be understood that the particular type and construction of the pneumatic hammer itself as to general features and mode of operation of its valve mechanism 50 are immaterial inasmuch as my invention concerns the working tool or rivet-set and the means for securing the same to the front end of the barrel or cylinder. However, for the purposes of a clear and definite description 55 of my invention I have shown the same

applied to a well-known Boyer riveting hammer such as exemplified in Boyer Patent No. 917,242 issued April 6, 1909, except insofar as the front end of the cylinder has been modified in order to embody my 60 invention. It will therefore suffice to state, but without any limitation to any specific structure, that the hammer comprises a barrel or cylinder 1 containing a longitudinal piston chamber 2, a reciprocable piston 3 65 therein, a handle 4 attached to the rear end of the cylinder and a distributing valve 5 governing the ports and passages for the admission and exhaust of the fluid to and from opposite ends of the piston chamber 70 including a series of ports 6 which extend to the front end of the cylinder and with which my invention is to some extent concerned.

The cylinder 1 is substantially the same 75 as the ordinary cylinder of a Boyer hammer with the exception, first, that it is shorter by omitting the extreme front end in which was formed the space or chamber containing the bushing for the shank of the ordinary rivet-set. In the present instance, the cylinder terminates at the front end of the piston chamber proper and the passages 6 terminate at such end, the same entering the piston chamber through the ports 7. Another exception 80 represented by the present construction is the reduction of the front end of the cylinder and the provision thereon of a series of coupling lugs 8 whose length is at right angles to the axis of the cylinder and which 85 are provided along their rearward edges with longitudinal recesses 8^a for a purpose hereinafter explained. In the present instance, there are three of these lugs although it will be understood that any desired number 90 thereof could be employed.

The working tool which in the present instance is a rivet-set 9 differs essentially from the ordinary rivet-set particularly in being unprovided with a shank and being 100 substantially a cylinder having at its outer end the usual cavity or recess to form the rivet-head and terminating at its rearward end in a marginal flange 9^a. This flange in the present instance corresponds in diameter 105 to the diameter of the front reduced end of the cylinder 1 and the inner face of the set bears against the front end face of the cylinder, thereby closing the front end of the piston chamber and the ends of the passages 110

6 so that the latter means communicate with the piston chamber through the ports 7. The rear face or head of the rivet-set thus is adapted to close the piston chamber for 5 returning the piston in the manner herein-after explained and it is in such position of course that the piston 3 delivers its impacts thereupon.

The rivet-set is held in place with relation to the barrel or cylinder by means of the sleeve 10 and the coiled spring 11. This sleeve fits upon the reduced end of the barrel or cylinder 1 and is provided at its rearward end with lugs 10^a adapted to coöperate with 15 the lugs 8 on the cylinder. The spaces 10^b intervening between the lugs 10^a of the sleeve are of such size as to accommodate the lugs 8 and after the sleeve has been thrust upon the cylinder to the full extent and when such sleeve is given a partial rotation the lugs 10^a will engage the lugs 8, being seated in the recesses 8^a thereof. This construction provides a simple but 20 efficient and easily-manipulated coupling means for attachment and detachment of the rivet-set.

The spring 11 is a coiled spring encircling the body of the rivet-set and bearing at its rearward end against the flange 9^a of the 30 set and its forward end against the inturned flange 10^c of the sleeve. This spring serves a threefold function, to wit, first, in holding the rivet-set in place against the front end of the cylinder, second, in cushioning or 35 absorbing the jar in case the hammer is accidentally operated and third in holding the lugs 8 and 10^a in their coöperating position.

When the hammer is operated in the well-known manner the piston reciprocates by 40 reason of the admission and exhaust of the motive fluid to and from opposite ends of the piston chamber. The front end of this piston chamber is formed by the head of the rivet-set so that the motive fluid delivered through the passages 6 will act upon 45 the piston to return it to the rearward end of the piston chamber for the next reciprocation or blow. The rivet-set thus closing the front end of the piston chamber receives 50 the impacts of the piston, which impacts are delivered directly upon the head of the short rivet-set instead of a shank of a rivet-set.

When it is desired to remove the rivet-set the sleeve is forced inwardly slightly and 55 then partly rotated so as to disengage the coupling lugs, whereupon the sleeve and the contained parts are readily removed.

By the use of my invention, I obtain many 60 advantages not only in matter of manufacture but also in actual use. Inasmuch as the blow of the piston is delivered directly upon the body of the set instead of a shank, greater power is obtained and the die is more durable even with less material. Thus, 65 there is overcome the serious objection to the

usual form of rivet-sets which break at the junction of the shank with the body of the set. Another advantage of my construction results from the shortening of the hammer barrel or cylinder and dispensing with the 70 usual chamber holding the shank of the die and the rivet-set bushing where trouble is experienced owing to the wearing of these parts, thus allowing the motive fluid to escape. By shortening the barrel or cylinder 75 material is saved and the weight of the hammer reduced without sacrificing power and inasmuch as the passages such as passages 6 extend directly through the barrel they are easier to drill and also easier to keep 80 clean. A further advantage of my invention consists in the fact that the hammer is made safe inasmuch as neither the piston nor the rivet-set can be expelled or detached from the hammer while it is in use, particularly when it is not actually pressed against the work.

I claim:

1. In a hammer, the combination, with a cylinder having a piston chamber and a reciprocable hammering piston therein and ports and passages for controlling the movements of the piston including passages whose front ends terminate at the front end of the cylinder and which have lateral communication adjacent such ends with the front end of the piston chamber, of a working tool normally closing the front ends of said latter passages, and means for holding the tool in operative position on the cylinder.

2. In a hammer, the combination, with a cylinder having a piston chamber and a reciprocable hammering piston therein and ports and passages for controlling the movements of the piston including passages whose front ends terminate at the front end of the cylinder and which have lateral communication adjacent such ends with the front end of the piston chamber, of a working tool having its rear face flat and normally closing the front ends of said latter passages and also the front end of the piston chamber, and means for holding the tool in operative position on the cylinder.

3. In a hammer, the combination, with a cylinder having a piston chamber and a reciprocable hammering piston therein and ports and passages for controlling the movements of the piston, of a working tool having a flat rear head fitting against the front end of the cylinder to receive the impacts of the piston, and yieldable means for holding the tool in position on the cylinder.

4. In a hammer, the combination, with a cylinder having a piston chamber and a reciprocable hammering piston therein and ports and passages for controlling the movements of the piston, of a working tool having a flat rear head fitting against the front

end of the cylinder to receive the impacts of the piston, and a spring for holding the tool in position on the cylinder.

5. In a hammer, the combination, with a cylinder having a piston chamber and a reciprocable hammering piston therein and ports and passages for controlling the movements of the piston, of a working tool having a flat rear head fitting against the front end of the cylinder to receive the impacts of the piston, and a sleeve partially inclosing the tool and fitting over and detachably connected with the cylinder.

6. In a hammer, the combination, with a cylinder having a piston chamber and a reciprocable hammering piston therein and ports and passages for controlling the movements of the piston, of a working tool having a flat rear head fitting against the front end of the cylinder to receive the impacts of the piston, said head being flanged and a sleeve partially inclosing the tool and having a front restricted opening through which the tool projects, the sleeve fitting over and being detachably connected to the cylinder.

7. In a hammer, the combination, with a cylinder having a piston chamber and a reciprocable hammering piston therein and ports and passages for controlling the movements of the piston, of a working tool having a flat rear head fitting against the front end of the cylinder to receive the impacts of the piston, said head being flanged, a sleeve partially inclosing the tool and having a front inturned flange to restrict the front opening through which the tool projects, and a spring encircling the tool and bearing

respectively against said flanged head and said flange of the sleeve.

8. In a hammer, the combination, with a cylinder having a piston chamber and a reciprocable hammering piston therein and ports and passages for controlling the movements of the piston, of a working tool arranged to fit against the end of the cylinder in position to receive the impacts of the piston, a sleeve fitting upon the front end of the cylinder and partially inclosing the tool, said sleeve having means of coupling to the cylinder including spaced lugs on the interior of the inner end of the sleeve, the front end of the cylinder having correspondingly spaced lugs to coöperate with the sleeve-lugs when the sleeve is partially turned.

9. In a hammer, the combination, with a cylinder having a piston chamber and a reciprocable hammering piston therein and ports and passages for controlling the movements of the piston, of a working tool arranged to fit against the end of the cylinder in position to receive the impacts of the piston, a sleeve fitting upon the front end of the cylinder and partially inclosing the tool, said sleeve having means of coupling to the cylinder including spaced lugs on the interior of the inner end of the sleeve, the front end of the cylinder having correspondingly spaced lugs to coöperate with the sleeve-lugs when the sleeve is partially turned, one set of lugs being recessed to receive and interlock with the other set.
